UNITED STATES PATENT OFFICE.

WILLIAM S. PETTY, OF DENVER, COLORADO, ASSIGNOR, BY DIRECT AND MESNE ASSIGNMENTS, TO KAY-PETTY MFG. CO.

IRONING TABLE.

Application filed June 27, 1927. Serial No. 201,656.

My invention relates to ironing tables, and is a companion to my ironing board invention, application for a patent on which is applied for on this date with this application.

Ironing tables are used for ironing lace curtains, sheets, table cloths, counterpanes and other large or long articles.

Even greater trouble is experienced with such articles in keeping them off the floor than with the smaller articles which are ironed on ironing boards.

Therefore, the object of my invention is to provide a practical self-contained ironing table which will keep all parts of any piece being ironed, from resting upon the floor, and which will be convenient and upon which good work may be performed at a high rate of speed, since no thought need be given by the operator to the matter of the goods becoming soiled.

In the drawings:—

Figure 1 is a view of my table looking down upon it from above.

Figure 2 is a section on the line 2—2 of Figure 1.

Figure 3 is a side view of my table, with a small portion in section.

Figure 4 is a section showing a detail of the apron frame mounting.

The board 1, which is of wood or other proper material, is supported on the legs 2, which are mounted on the cross feet 3.

The legs are braced by the brace 4, which is securely attached to the legs and to the board in any proper manner. But, whatever the construction and bracing of the table support, it should be such as to give the proper amount of both lateral and longitudinal strength and rigidity to the table.

The board 1 is to be covered by padding of any proper material, the cover 5 thereof to be hooked on the pins 6, which are imbedded in the board 1, as shown in Figure 2. Or the cover may be mounted in any other proper manner, so long as it is properly held upon the board.

The board is provided with the light

bracket 7, which carries the main line plug 8, the pilot light 9, the switch 10, and the electric iron plug 11.

The electric cable 12 connects the main line plug 8 with a source of electric current. The switch 10 connects or disconnects this current to the electric iron plug 11 and the pilot light 9. The electric cable 14 carries the electric current to the electric iron 15.

The apron frame end 16' is provided with slots 17 through it end pieces. The slots 17 receive the rollers 18 through which pass the bolts 19. See Figure 4.

The bolt 19 is provided with a reduced end which passes through the table leg 2, and is held firmly therein by the nut 20 and the washer 21. The washer 22 under the head of the bolt 19 maintains the frame 16 in place on the bolt and roller.

Because of this mounting of the frame ends 16' on the table, the frame 16 may be moved with respect to the table, as will appear below.

The apron rods 23 are received by small cavities in the frame ends.

When the apron 24, preferably of muslin, canvas or other cloth, becomes soiled, it may be removed from the rods 23 by raising the rods from the cavities in the frame ends and pulling them from the loops 25. The new clean apron is replaced by pushing the rods through the apron loops and then dropping the rod ends into the cavities of the frame ends.

The apron 24 may be made of metal or any other proper material, if desired, but I prefer the use of muslin, canvas, or other cloth as stated above.

The corners of the frame 16 are braced by the angle pieces 26, which are attached to the side and end frame pieces.

The mounting of the apron on the frame, and of the frame on the table may be modified as desired so long as the apron may be moved laterally with respect to the table.

In the operation of my table, the apron is pulled toward the operator and the lace curtain, or other article is placed therein, one end of it being placed upon the table.

The apron is then pushed away from the operator till its remote edge extends out from the remote edge of the table.

The piece may then be ironed, and as it is moved across the table it will fall into the apron, while on the other side of the table the material will be continually pulled up out of the apron and upon the board for ironing.

10 Thus, no matter how long the article is, the portion yet to be ironed will be carried in the apron, and the portion already ironed will be caught and held in the apron.

As the construction of the table and apron 15 is symmetrical the operator may stand upon either side with equally good results.

The apron being so much closer to the top of the table than a receptacle or basket resting on the floor, the entire performance of 20 drawing the material from the apron and of allowing it to fall down into the apron again after it is ironed, has more certainty and less chance of the material being harmed or soiled.

25 I do not wish to be narrowly held to the exact details of construction shown and described, but what I claim as new, and desire to protect by Letters Patent, is as follows:—

1. In combination, a table provided with 30 a top having supports at both ends, a frame mounted upon the supports and adapted to move laterally beneath the top and to extend selectively to either one side or the other thereof, and means attached to the 35 frame and forming therewith a receptacle.

2. The combination of a table composed of a top, and legs supporting the top at both ends thereof, pins mounted on the legs, sleeves rotatably mounted on the pins, a

frame having two sides and two ends under 40 the top, the ends provided with horizontal slots in which said pins and sleeves are movably received, and a fabric attached to the frame and forming therewith a receptacle laterally movable with respect to the top. 45

3. In combination, a table provided with a top, having supports at both ends, a frame comprising end pieces joined by side pieces, means mounting the end pieces on the said supports and adapted to permit movement of the end pieces whereby the frame may be moved laterally beneath the top and to extend selectively to either one side or the other thereof, and means attached to the frame, and forming therewith a receptacle. 50 55

4. The combination of a table comprising a top and legs supporting the top at both ends thereof, pins mounted on the legs, a frame having two sides and two ends under the top, means adapted to co-operate with said pins and said two ends of the frame to support the frame and permit its lateral movement beneath the top, and a fabric attached to the frame and forming therewith a receptacle laterally movable with respect 60 to the top. 65

5. In combination, a table provided with a top having supports at both ends and forming therewith a unit, a frame having joined side pieces and end pieces slidably 70 mounted by said end pieces on said supports of said unit and adapted to move laterally beneath the top and to extend selectively to either one side or the other thereof, and means attached to the frame and forming 75 therewith a receptacle.

In testimony whereof I affix my signature
WILLIAM S. PETTY.
